(57) **CLAIM**

The ornamental design for a hair dryer with pivoting and turnable handle, as shown and described.

DESCRIPTION

FIG. 1 is a perspective view generally taken from the bottom of the hair dryer showing a hair dryer with a pivoting handle that may be pivoted 90° into a folded position and turned 180°;

FIG. 2 is a perspective view generally taken from the top of the hair showing the design;

FIG. 3 is a top plan view thereof;

FIG. 4 is a front elevational view thereof;

FIG. 5 is a back elevational view thereof;

FIG. 6 is a side elevational view thereof;

FIG. 7 is the side view of FIG. 6 illustrating the handle turned 90°;

FIG. 8 is the side view of FIG. 6 illustrating the handle turned 180°;

FIG. 9 is the side view of FIG. 8 illustrating the handle in an alternate folded position; and,

FIG. 10 is the side view of FIG. 6 illustrating the handle in a completely folded position.
